United States Patent Office.

E. EMMERT, OF FRANKLIN GROVE, ILLINOIS.

Letters Patent No. 73,788, dated January 28, 1868.

IMPROVEMENT IN HARVESTERS.

The Schedule referred to in these Letters Patent and making part of the same.

TO ALL WHOM IT MAY CONCERN:

Be it known that I, E. EMMERT, of Franklin Grove, in the county of Lee, and State of Illinois, have invented a new and useful Improvement in Harvesters; and I do hereby declare that the following is a full, clear, and exact description thereof, which will enable those skilled in the art to make and use the same, reference being had to the accompanying drawings, forming part of this specification, in which—

Figure 1 is a side sectional view of my invention, taken in the line $x x$, fig. 2.

Figure 2. a plan or top view of the same.

Figure 3, a vertical section of the same, taken in the line y y , fig. 1.

Stipple letters of reference indicate corresponding parts.

Similar letters of reference indicate corresponding parts.
This invention relates to improvements in harvesters, and consists in the combination of the fingers and cutter-bar with the notched pitman, when the latter is pivoted to the outer end of the cutter-bar, for the purpose of scattering the cut grass, as will be hereinafter more fully described.

A represents an axle, having a wheel, B, on each end of it, and pendent bars *a* attached, to which the platform-frame C is secured. D is a beam, the rear end of which is connected by a joint, *b*, with the axle A, said beam being braced by a bar, *c*, which is also connected with the axle by a joint, *d*. The front end of the beam D is supported by a truck, E^X, the axle *e* of which turns on a king-bolt. On the beam D, near its front end, there are secured two uprights, *ff*, between which a wheel, E, is placed, the axis of said wheel having its bearings in the upper parts of the uprights. To this wheel E arms *g* are attached, between which the driver's seat, F, is secured, in such a manner that it may be adjusted further forward or backward, as may be desired. The wheel E is connected by a chain, *h*, to the upper ends of bars *i i*, which are attached to the front end of the platform-frame C, at the right-hand side thereof. One of the wheels B is provided at its inner side with a concentric toothed rim, *j*, into which a pinion, F, gears, said pinion being on a shaft, G, which has a bevel-wheel, *k*, upon it, the wheel *k* gearing into a bevel-pinion, *l*, on the inner end of the shaft of a drum, H, which is below and parallel with the beam D. The front end of the shaft of drum H is made in the form of a crank, *m*, and has a pitman, I, attached, which extends to the outer end of the sickle J, and is connected thereto by a suitable joint, *n*. The sickle J is fitted and works upon a finger-bar, K, as usual, and the upper edge or surface of the pitman is formed with ratchet-shaped teeth, *o*. L represents an endless carrier, which is directly back of and parallel with the finger-bar K, and works over a roller, *j'*, at the outer or grain-end of the platform-frame C, and over a roller, *q*, at the upper ends of standards *f^X f^X*, the lower ends of which are framed into the right-hand side of the platform-frame C. This roller *q* is elevated considerably above the platform-frame C, as shown clearly in fig. 3, and the carrier L is kept in a horizontal position directly behind, and for a distance equal in length to the sickle, by means of the drum H, as will be fully understood by referring to fig. 3, the ends of the drum having enlarged portions, *s s*, which bear upon leather selvedges, *t*, on the carrier. The carrier is driven by a cross-belt, *u*, from the drum H, and over the inclined part of the carrier there is a short metal guide-plate, M, the upper end of which works on a rod, *v*, to admit of said plate yielding or giving to conform to the varying thickness of the layer of grain carried up by said inclined portion of the carrier, and an elastic guiding strip, N, is attached to the rod *v*, said strip extending downward, and serving to guide the cut grain upon the binder's platform.

It will be seen that the driver, by moving further backward or forward on his seat, F, may balance or counterpoise the sickle in order that it may rise and fall freely, and conform to the inequalities of surface over which it may pass, and also allow said sickle and the finger-bar to pass obstructions which may lie in their path. The seat F may also be adjusted further forward or backward between the arms g g, to suit the weight of the driver. The pitman I, in consequence of being attached to the outer end of the sickle J, is of considerable length, and operates the sickle with less friction, less wear and tear, and is less liable to break, and its upper serrated or toothed edge, over which the cut grass falls, serves to scatter and spread the latter effectually. The pitman is made without notches, when the device is used as a harvester.

The device, as a whole, is extremely simple and efficient, may be constructed at a moderate cost, and there are no parts liable to become deranged by use, or to get out of repair.

no parts liable to become deranged by use, or to get out of order, and described my invention, what I claim as new, and desire to secure by Letters Patent, is—

The combination of the fingers and cutter-bar with the notched pitman, when the latter is pivoted to the outer end of the cutter-bar, for the purpose of scattering the cut grass, as herein shown and described. E. EMMERT.
